UNITED STATES PATENT OFFICE

2,598,575

VENETIAN BLIND

Joseph K. Martin, Marietta, and David W. Doughty, Atlanta, Ga., assignors to Thompson Venetians, Inc., Atlanta, Ga., a corporation of Georgia

Application March 26, 1951, Serial No. 217,426

2 Claims. (Cl. 160—178)

1

This invention relates to Venetian blinds. In a Venetian blind construction, a bottom rail is provided which is secured to the tapes and to the raising and lowering cords. Where the slats are made of metal, a wooden bottom rail is used and the tapes are tacked to the lower side of the bottom rail. It is, therefore, an object of this invention to provide a metal bottom rail with an improved means for securing or clamping the tapes thereto in addition to an improved means for securing the cords thereto.

Another object of this invention is to provide an improved bottom rail which is formed of an inverted channel member, a clamping strip having an ogee curvature in transverse section, and a transversely curved closure strip, with removable end caps for closing the open ends of the bottom rail.

A further object of this invention is to provide an improved bottom rail which will speed up production and assembly including repair to Venetian blinds.

With the above and other objects in view, our invention consists in the arrangement, combination and details of construction disclosed in the drawings and specification, and then more particularly pointed out in the appended claims.

In the drawing,

Figure 1 is a fragmentary plan view partly in section of a bottom rail for a Venetian blind constructed according to an embodiment of this invention;

Figure 2 is a sectional view taken on the line 2—2 of Figure 1; and

Figure 3 is a sectional view taken on the line 3—3 of Figure 1.

Referring to the drawing, the numeral 10 designates generally a bottom rail for a Venetian blind which is secured to the lower ends of slat-supporting tapes generally designated as 11. The tapes 11 include vertically disposed tape members 12 having secured therebetween slat-supporting ladders 13. The bottom rail 10 is formed of an elongated inverted U-shaped or channel member 14 provided between the longitudinal edges thereof with downwardly extended ribs 15 and the vertical sides 16 of the U-shaped member 14 are provided with downwardly and inwardly inclined flanges 17.

The tapes 12 as extended downwardly over the side members 16 and under the flanges 17 and are then extended inwardly and outwardly as indicated at 18 over the upper sides of the flanges 17. The tapes 12 at their lower ends within the channel member 14 are disposed in

2

overlapping position and the overlapping ends of the tapes are stapled together, as indicated at 19. A tape clamping member, generally designated as 20, which is of ogee configuration in transverse section, is disposed within the channel member 14, and the tape clamping member 20 is formed with a substantially parabolic central portion 21 having downturned and outwardly curved opposite end portions 22. The 10 opposite longitudinal edges of the clamping member 20 are adapted to bind the tape extensions 18 against the inner sides of the flanges 17 and the upper convex sides of the end portions 22 are adapted to bind the tape against 15 the lower side of the upper wall 23 of the channel member 14. A transversely curved closure plate 24 is extended into the channel member 14 from one end thereof and binds on the upper sides of the tape extensions 18 with the convex 20 upper side of the closure member 14 bearing against the lower convex side of the parabolic central portion 21. The opposite ends of the bottom rail 10 are adapted to be closed by means of a pair of caps 25 which frictionally engage 25 the opposite ends of the channel member 14 and extend beneath the closure plate 24. The top wall 23 of the channel member 14 is provided at spaced intervals with keyhole openings 26 which include a relatively restricted intermediate portion 27.

A cord 28 having a knotted lower end 29 is adapted to be extended through the opening 26 and then moved laterally through the restricted portion 27 to the reduced diameter portion 30, 30 wherein the cord 28 will be normally positioned.

In the use of this bottom rail structure, the tapes 12, which are secured as by staples 19 together at their lower ends, are extended about the inverted U-shaped member 14 and the tape clamping member 20 is then snapped into position in the channel member 14 beneath the connected together tapes 12 so that the tapes 12 will be resiliently bound within the channel member 14. The bottom plate 24 is then also inserted from one end of the channel member 14 whereupon the closure caps 25 may be slipped over the ends of the channel member 14. The cords 28 may be engaged with the top wall of the channel member 14 by extending the knot 45 29 through the keyhole openings 26 and moving the cord 28 through the restricted portion 27 into the reduced diameter opening 30.

This bottom rail is designed to be manufactured of metal and will provide an improved means for holding the tapes of Venetian blinds

in addition to speeding up the assembly, repair or change in size of the bottom rail where the rail is to be cut off in order to fit a selected opening.

What is claimed is:

1. In a Venetian blind structure having slat supporting tapes, a bottom rail comprising an inverted U-shaped member, inwardly projecting flanges carried by the lower edges of the vertical sides of said member, and an elongated tape 10 clamping member engageable within said U-shaped member, said clamping member being reversely curved in transverse section with the outer portions thereof downwardly directed to thereby bind the tape against the inner sides of 15 said flanges.

2. In a Venetian blind structure having slat supporting tapes, a bottom rail comprising an inverted U-shaped member, inwardly projecting flanges carried by the lower edges of the vertical 20 sides of said member, an elongated tape clamping member engageable within said U-shaped

member, said clamping member being reversely curved in transverse section with the outer portions thereof downwardly directed to thereby bind the tape against the inner sides of said flanges, and a transversely curved closure strip engaging the inner sides of said flanges.
